UNITED STATES PATENT OFFICE

113,086

DESIGN FOR A CURTAIN

Frederich Gentner, Philadelphia, Pa.

Application July 22, 1938, Serial No. 78,654

Term of patent 3½ years

To all whom it may concern:

Be it known that I, Frederich Gentner, a citizen of the United States of America, residing in Philadelphia, county of Philadelphia, and State of Pennsylvania, have invented a new, original, and ornamental Design for a Curtain, of which the following is a specification, reference being had to the accompanying drawing, forming part thereof, wherein, the figure is a plan view of a complete curtain showing my new design.

The design is characterized by the specific floral border with the specific fringed curtain as shown.

I claim:

The ornamental design for a curtain, substantially as shown, and described.

FREDERICH GENTNER.
